United States Patent Office

Des. 179,685
Patented Feb. 12, 1957

179,685

DESK OR THE LIKE

Alfred C. Hoven, William S. Lindberg, and Walter E.
Nordmark, Grand Rapids, Mich.

Application May 18, 1955, Serial No. 36,086

Term of patent 14 years

(Cl. D33—11)

Fig. 2

We claim:

The ornamental design for a desk or the like, substantially as shown.
